UNITED STATES PATENT OFFICE.

LESTER C. HART, OF CLEVELAND, OHIO, ASSIGNOR TO HI-VOLTAGE EQUIPMENT COMPANY, A CORPORATION OF PENNSYLVANIA.

HIGH-VOLTAGE SWITCH.

Application filed July 2, 1927. Serial No. 203,047.

The invention relates to high voltage switches, and particularly to those of large size, although certain features are equally advantageous in small switches. It has for 5 its principal objects, the provision of a switch of the type specified having a better balance than those heretofore constructed, so that the switch is easier to close and is held closed securely by gravity when once closed. This 10 feature of balance is important in large size switches of the type specified, as these switches, having a plurality of poles, are ordinarily operated in multiple from a single handle, so that it becomes a difficult matter 15 to operate the handle and swing the heavy switch arms to closed position against gravity. Briefly stated, the balancing, or counterbalancing effect is secured by locating the heavy insulator, which carries the 20 switch arm or operates it by its rotation, off center with respect to its center of rotation, so that the weight of the insulator tends, (1) to close the switch arm, and (2) to hold it closed when once shut, so that there is no 25 danger of the switch opening itself accidentally. Certain embodiments of the invention are illustrated in the accompanying drawings, wherein:

Figure 1 is a side elevation with the switch 30 in closed position. Fig. 2 is a detail diagrammatic view showing the relation of the center line of the insulator to the axis of rotation thereof. Fig. 3 is a perspective view showing the switch in full open position. And 35 Figs. 4 and 5 are perspective views showing a modification with the switch arm in closed position in Fig. 4 and in open position in Fig. 5.

Referring to Figs. 1, 2 and 3, 1 is the vertical base upon which are mounted the insulators 2 and 3, the insulator 2 being fixed 40 in position upon the upper end of the base, while the insulator 3 is mounted for rotation upon the axle 4, and carries at its outer end the switch arm 5. As indicated in Figs. 1 and 3, a rotation of about 60 degrees moves the switch arm from closed position to full open 45 position. Connected to the metal blocks or caps at the outer ends of the insulators are the current terminals 6 and 7. The axle 4 is provided with the crank arms 8 and 9 secured to the connecting rods 10 and 11, one of which supplies the power to rotate the axle, and the other of which is connected to the 50 next switch of the series.

As indicated in Figs. 1 and 2, the axis of rotation 12 of the axle is off center with respect to the center line 13 of the insulator 3, the relative positions of these centers being indicated in Fig. 2, wherein the parts are 60 shown in the position occupied when the switch arm is in closed position (Fig. 1). As the switch arm is opened by a movement in a clockwise direction, the weight of the insulator, therefore, tends to hold the switch 65 closed, as it tends to swing the arm in a counter clockwise direction. There is thus no danger of the arm swinging open accidentally, any vibration to which the switch is exposed, tending to make the arm move in the 70 contrary direction.

When the switch arm is moved to open position, the center 13 of the insulator (which is also its center of gravity) is moved to the position 14 of Fig. 2. In this position, the 75 weight of the insulator still lies to the left of the vertical line 15 extending through the axes of rotation 13 of the axle, so that such weight still tends to rotate the axle in a counter clockwise direction. The weight of the 80 insulator thus counterbalances the weight of the switch arm 5, and the power required to close the arm is materially reduced. This becomes important, as heretofore referred to when the switches are arranged in multiple, 85 due to a number of poles, and are of very large size. For instance, with the counterbalancing feature, one man can without difficulty operate a six pole switch running up to the 132,000 volt size, while without this feature 90 of construction, it is practically impossible for one man to operate such a switch.

Figs. 4 and 5 illustrate a modification embodying the same counterbalancing feature. Here the base 16 is also vertical, and the 95 switch arm 17 is vertical or upright, when in closed position. The current terminals 18 and 19 are carried by metal caps or blocks at the outer ends of the insulators 20 and 21 mounted in fixed position at the ends of the 100 base or frame 16. A third insulator 22 is mounted upon the crank arm 23 swung by means of a crank arm 23^a and a suitable connecting rod pivoted to the end of such latter crank arm, as in the other type of construction. The upper end of the insulator 22 is supported from the insulator 20 by a tie rod 24 pivoted to the caps or blocks at the ends 105 of the insulators to accommodate itself to the swinging movement of the insulator 22. The 110

switch arm 17 is pivoted to the cap on the insulator 20 and is swung up and down by a crank arm 25 connected to a crank arm 26 carried by the cap of the insulator 2, by means 5 of the rod 27, the connections at the ends of the rod comprising suitable universal joints to provide for the necessary relative movements between the parts.

When the switch is closed, as shown in 10 Fig. 4, the weight to the insulator tends to rotate the cranks 23 and 26 in the direction indicated by the arrows (Fig. 4), the crank 26 being so located that this movement tends to move the rod 27 in the direction of its length 15 toward the insulator 21. The weight of the insulator thus tends to hold the switch arm 17 closed, and also tends to move such arm to closed position from open position. When the switch arm is moved to full open position 20 (by turning the cranks, as indicated by the arrows in Fig. 5), the axis of the insulator 22 lies almost directly above the axis of rotation of the crank 23, so that the weight of the insulator exerts very little pull in either direction, the weight of the switch arm serving to 25 hold it in open position. In moving from such point until the arm is closed, the weight of the insulator assists in closing, as above indicated.

30 What I claim is:

1. In combination in a high voltage switch, a pivoted switch arm which occupies a substantially vertical position when closed, an axle mounted for oscillation and adapted by such oscillation back and forth to open and 35 close the switch arm, and an insulator carried by the axle and supporting the switch arm, said insulator being positioned with its center of gravity, when the axle is in both extremes of oscillation, on the same side of the 40 vertical plane in which the axis of the axle is located and tending by its weight to swing the switch arm to closed position.

2. In combination in a high voltage switch, a pivoted switch arm which occupies a substantially vertical position when closed, an axle mounted for oscillation and adapted by such oscillation back and forth to open and close the switch arm, and an insulator carried by the axle and operatively connected to 45 the switch arm, said insulator being positioned with its center of gravity, when the axle is in both extremes of oscillation, on the same side of the vertical plane in which the axis of the axle is located and tending by 50 its weight to swing the switch arm to closed position.

In testimony whereof, I have hereunto subscribed my name this 30th day of June, 1927.

LESTER C. HART.
